United States Patent Office

Des. 198,791
Patented Aug. 4, 1964

198,791

MEDALLION OR SIMILAR ARTICLE

John S. Stephens, 60 Armour Road, Mahwah, N.J.

Filed June 12, 1961, Ser. No. 65,572

Term of patent 14 years

(Cl. D29—19)

Fig. 1

Fig. 2

Fig. 3

Fig. 4

Fig. 5

The rear of my medallion is arcuate, smooth and without ornamentation.

The dominant features of my design reside in those portions of the drawing shown in full lines.

I claim:

The ornamental design for a medallion or similar article, as shown and described.
